CLAIM

The ornamental design for a closure clip, as shown and described.

DESCRIPTION

FIG. 1 is a front perspective view of the closure clip; FIG. 2 is a top view of the closure clip; FIG. 3 is a bottom view of the closure clip; FIG. 4 is a front view of the closure clip; FIG. 5 is a rear view of the closure clip; FIG. 6 is a left side view of the closure clip; FIG. 7 is a right side view of the closure clip; and, FIG. 8 is a front perspective view of the closure clip mounted on a reclosable pouch.

The broken lines in FIG. 8 illustrating a reclosable pouch depict environment only and form no part of the claimed

(Continued)

design. All other broken lines in the drawings depict portions of the closure clip that form no part of the claimed design.

1 Claim, 6 Drawing Sheets
